UNITED STATES PATENT OFFICE.

JOHANNES BENJAMIN EEN, OF VOSS, NORWAY.

JOINT-CLOSURE.

1,389,557.

Specification of Letters Patent.

Patented Aug. 30, 1921.

Application filed February 18, 1920. Serial No. 359,535.

To all whom it may concern:

Be it known that I, JOHANNES BENJAMIN EEN, a subject of the King of Norway, residing at Voss, Norway, have invented certain new and useful Improvements in Joint-Closures, (for which I have filed an application in Norway, No. 11,336, July 25, 1917;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to an improved joint closure for joints especially in wooden constructions of the kind in which there are comparatively few joints as, for instance, houses built up of ready made wall sections.

The joint closures which may be made from paper, cardboard or any other suitable material, are folded in such way as to allow of their widening and contracting in conjunction with the alterations in the width of the joint in which they are placed.

In the accompanying drawings there is illustrated a cross sectional view of an exemplification of one form of my invention.

In the form shown in the drawing the joint closure is made in the form of a closed paper tube 3, preferably provided with folds

4 and with layers of glue or gum, 5, on diametrically opposite sides thereof. By using a closed tube two tightening faces are obtained instead of only one, and also an insulating air space.

It will be observed that by forming the joint closing member of paper of expandible formation and using an adhesive material for securing it to the contiguous edges of the boards, the adhesive material also forms a seal between the sides of the closing member and the edges of the boards, which would not be possible if the closing member were made of metal.

Claim:

The combination with a wall formed of a plurality of boards placed in edge-abutting relation, of a joint closing member between contiguous edges, said member comprising a paper tube, and a layer of glue on diametrically opposite exterior sides of said member for fastening it directly to said edges, said glue also forming a seal between the sides of the closing member and the contiguous edges of the boards.

In testimony that I claim the foregoing as my invention, I have signed my name in presence of two subscribing witnesses.

JOHANNES BENJAMIN EEN.
